UNITED STATES PATENT OFFICE.

WILLIAM H. MUZZY, OF DETROIT, MICHIGAN.

FUEL-FEEDING DEVICE FOR AUTOMOBILES.

1,222,235.

Specification of Letters Patent. Patented Apr. 10, 1917.

Application filed April 1, 1915, Serial No. 18,533. Renewed March 1, 1817. Serial No. 151,831.

To all whom it may concern:

Be it known that I, WILLIAM H. MUZZY, a citizen of the United States, residing at Detroit, in the county of Wayne and State of Michigan, have invented certain new and useful Improvements in Fuel-Feeding Devices for Automobiles, of which I declare the following to be a full, clear, and exact description.

10 This invention relates to improvements in motor vehicles and has more particular relation to improvements in mechanisms, systems and devices for the feeding of liquid gasolene to the carburetors of gas engines.

15 One of the objects of the invention is the improvement of the mechanisms and devices at present employed in the so called "vacuum systems" for feeding gasolene from a relatively low main supply tank to the carburetor of the engine and also the improvement of the devices shown in my co-pending application Number 15895 of 1915 filed March 20, 1915, on vacuum fuel feeding systems.

20 25 Another object of the invention is the improvement of the devices shown in my aforementioned pending application by the introduction into the air and gasolene circulating pipes of an automatic dam for obstructing the flow in one direction.

30 35 Another object of the invention is the peculiar construction of the three tanks whereby they may be assembled into a rigid unit but in such manner that they may be instantly taken apart or separated at will without the breaking of soldered or other permanent connections.

40 45 A further object is the provision of an overflow pipe by which gasolene is discharged into the lower tank from the intermediate tank without the use of a siphon as in my first mentioned application.

Another object of the invention is the provision of means for causing the tank to fill by the operation of the engine even though the tank is entirely empty when the operation is started.

In carrying these and other objects of the invention into effect I utilize certain constructions, combinations and arrangements

of parts all of which will be hereinafter more particularly set forth but it will be readily understood that many of these may be varied and other similar devices employed without departing from the spirit of the invention.

In the accompanying drawings forming part of this specification:

Figure 1 represents a central vertical section through a cylindrical tank embodying my invention, and

Fig. 2 represents a similar section, partly broken away, of a modified form of tank with an automatic atmosphere valve.

As in my aforesaid pending application, 65 this improved tank is connected to the main supply tank at the rear of the machine by a pipe 5, to the carburetor of the engine by a pipe 6 and to the intake manifold of the engine by a pipe 4. These connections are 70 substantially in the same manner as described in my said co-pending application with the exception that the pipe from the main supply tank enters the vacuum tank from the top of the tank.

In general terms these connections may be described as drawing the gasolene, by suction, from the main tank at the rear into the vacuum tank of my improved device, then allowing the gasolene to pass by gravity first into an intermediate tank and finally into a carburetor supply tank.

In the said drawings 1 represents the outer tank or containing shell, 2 the vacuum tank proper, 3 the intermediate tank, 4 the suction pipe, 5 the main supply pipe, 6 the pipe from the tank to the carburetor, 7 the atmospheric valve, 8 the stand pipe or overflow, 9 the vacuum tank discharge pipe and 10 the vacuum tank vent or air pipe.

The outer or containing tank 1 is preferably cylindrical in form but it will be readily understood that it may be rectangular in shape if desired. This tank is provided with attaching lugs 11 by which it may be supported in proximity to the engine and at a suitable elevation above the carburetor.

The vacuum tank 2 is closed air tight by a cover 12 which is secured in position by

75

80

100

bolts 13 which pass therethrough and also through a flange 14 on the tank 2 and a flange 15 on the tank 1 thus securing all the parts together and sealing both the tank 2 and the tank 1 with an air tight joint.

The tank 2 rests also upon the partly closed top of the tank 3 which is first placed in the tank 1, resting upon the bottom of the tank 1 by means of supporting legs with 10 which it is provided. These legs 16 are formed at their lower ends with feet 17 which rest upon the bottom of the tank 1.

The vacuum tank 2 is provided with two vertical pipes 9 and 10 made fast thereto and 15 each of which is provided with a vertically operating dam or governor 18. Each of these dams consists of a light rod having a disk 19 at each end. The length of the rod in each instance is such that only one 20 of the disks connected to it can be in contact with one end of its respective pipe at the same time, the opposite disk at this time being slightly separated from the opposite end of the pipe as shown in Fig. 1 of the 25 drawings. The office of these dams or governors is to dam or regulate the flow of liquid through the pipes 9 and 10. They permit of a very small amount of liquid being drawn up into the vacuum chamber at 30 a time but at the same time permit the liquid in the vacuum chamber to pass rapidly to the other chambers through the same pipes. Each of the pipes 9 and 10 is formed at its upper edge with slots 20 while the pipe 9 35 is formed at its lower end with a slot 21.

The tank 3 is provided with the stand pipe 8 fast therein so that when the tank fills it will overflow into the tank 1. The stand pipe is formed with a small aperture 22 40 located a suitable distance below its upper end so that the discharge through the stand pipe will continue even after the liquid in the tank 3 has descended below the upper end of the stand pipe. The purpose of this 45 construction is to continue to empty liquid into the tank 1 even after the lower end of the pipe 10 has been covered and the feed down the pipe 9 thus stopped as will be hereinafter described. This is possible as 50 the feed down the pipe 9 is much faster than the aperture 22 alone can take care of and the liquid thus rises in the chamber 3 until it finally overflows the top of the pipe 8.

The tank 3 is also provided with a sleeve 55 23 fast thereto and extending down into the tank 1, the pipe 10 being located inside of this sleeve to prevent any splash from the main tank 1 from closing the lower end of 60 the pipe before the main body of the liquid reaches it. This sleeve 23 also enables the tanks to be assembled by allowing the pipe 10 to pass through the tank 3 without any soldering or joints that may leak. The tank

3 is also formed near its upper end with air 65 ports 24 so that it may receive atmospheric pressure air from the tank 1 at these points. The sleeve 23 is also formed near its upper end with an air port 25 for preventing any trapping of air in the upper end of the 70 sleeve after the liquid starts to rise in the sleeve.

It will be seen by reference to Fig. 1 that the tank 1 is sealed except for an air vent 75 pipe 26 located near its upper end and provided with a valve 7 operated by a rod 27 which extends to within easy reach of the operator of the machine. The office of this valve 7 is to compel the tanks to be filled again if for any reason they become empty 80 at any time, such for instance as running out of gasoline or when the machine is first put into operation. The closing of the valve 7 will cause the suction created by the pipe 4 to fill the tanks 1 and 2 to their operative 85 levels when the valve 7 is again opened and the automatic operation renewed.

In the modified form of my invention shown in Fig. 2 I provide a cork float 28 90 in the carbureter supply tank, and mounted on a rod 29. The tanks 2 and 3 in this construction are made narrower to permit this rod 29 to pass up beside them. The rod is provided at its upper end with a ball valve 30 and is guided at its upper end by passing through a valve seat 31 secured in the top of the tank. The valve is arranged to seat on this valve seat when the float 28 descends because of the gasoline passing out 95 of the tank 1 as it does when the main supply tank at the rear becomes exhausted. When the valve 30 closes in this way the same operation takes place as when the valve 7 is closed by hand. The valve 30 is protected by a screw cap 32 having apertures 33 100 to permit air to pass freely to the valve seat when the valve is ordinarily open as shown in Fig. 2. The lower end of the rod 29 is guided by a lug 34 fast to the bottom of the tank 1.

Drain plugs 35 and 36 are mounted in the bottom of the tank 1 and in the top of the tank 3 so that the tanks may be cleaned of dirt or sediment without taking them apart.

The operation of the devices shown in Fig. 1 is as follows: The suction in the tank 2, created by the pipe 4, causes both dams 18 to rise into the positions shown and thus blocks the lower end of the pipes 9 and 10. A slight amount of gasoline will escape upward between the disk 19 and the lower end of the pipe 10 as this is not a close joint but simply a loose fit to prevent any large amount of gasoline from passing up the pipe. Gasoline will now pass up the pipe 9 into the tank 2 through the slot 21, a slight amount passing the disk 19 also as in the case of the pipe 10. The amount

of gasoline that is allowed to pass upward into the tank 2 however is not sufficient to balance the vacuum and gasoline is thus drawn from the main supply tank through the pipe 5 into the tank 2 as shown in Fig. 1 and the tank thus replenished. The operation continues until the gasoline in the chamber 3 is so far removed that the port or slot 21 is uncovered when air will pass up the pipe 9 through the gasoline in bubbles and destroy the vacuum in the tank 2 and stop the pumping through the pipe 5. The tank will then remain inoperative until the level of the gasoline in the tank 1 descends below the lower end of the pipe 10 when air will start to pass up said pipe, the dams 18 having dropped to their lower positions when air started to pass up the pipe 9. When air passes up either the pipes 9 or 10 it escapes at the upper end through the slots 20. When the air starts to pass up the pipe 10 it stops passing up through the gasoline in the pipe 9 and the gasoline in the tank 2 begins to pass down through the pipe 9 and out at its lower open end, the gasoline passing under the upper disk 19 and through the slots 20. The gasoline continues to pass down the pipe 9 into the chamber 3 until the stand pipe 8 overflows and raises the level of the gasoline in the tank 1 so that it again closes the lower end of the pipe 10. Just as soon as the lower end of the pipe 10 is closed both of the dams 18 jump upward into the positions shown in Fig. 1 and close the lower ends of the pipes and the operation is repeated. The upward movement of the dams 18 is caused by the suction and the upward movement of the gasoline in the pipes, this gasoline striking the upper disks 19 with considerable force and raising the dams into position where they are held by the suction. When the dams are released they are of sufficient weight to return promptly to their lower positions.

At each pumping operation more gasoline is pumped into the tank 2 than is taken out of the tank 1 for use and the level in the tank 2 is thus raised until finally it passes above the upper end of the pipe 10. When this takes place the gasoline passes down the pipe 10 into the tank 1 as the air passes up the pipe 9 and the surplus gasoline is thus used to block the lower end of the pipe 10 and prevent any further pumping until all this gasoline is used, when the operation is repeated. By this means the tank can never overpump itself.

It will be observed that the dams 18 are practically trouble proof as they do not have to be closely seated on the ends of the pipes and can be roughly made and operate perfectly. There is no chance of them sticking by the presence of dirt or other foreign

matter as the rods are so much smaller than the pipes through which they pass. If any dirt should by any means lodge under the upper disks 19 no harm would be done as these disks simply act to limit the downward movement of the dams and receive the impact of the gasoline to move the dams upward. The chances for dirt lodging under the bottom of the pipe 10 is very remote and even if dirt did lodge at this point the tank would still operate perfectly. Its periods of operation would simply be closer together. As the dams move laterally and are constantly changing their points of contact with the pipes 9 and 10 any particles of dirt are scraped off and washed by the streams of gasoline into the lower tank. There are no fine working points whatever that might be affected by the presence of dirt.

The pipe 6 connects the bottom of the tank 1 with the carbureter of the engine and the tank 1 must therefore be located slightly above the level of the carbureter.

Both the hand valve and the automatic atmospheric valve do not come into use at all in the ordinary operation of the tank but are used only in emergencies, such for instance as when the supply in the main gasoline tank is allowed to run out. When a leaky carbureter drains all of the gasoline out of the tank 1 overnight the valves come into play. When the tank is being first filled after the machine has been sold the valves come into play. It will be understood that if the supply of gasoline in the supply chamber should be depleted faster than it is renewed, the valve 30 will automatically come into operation, close the air inlet into the supply chamber and cause the tank to pump continuously until the level in the supply chamber has risen to cover the lower end of the pipe 10, when the regular action will be resumed. During this operation the gasoline pumped into the vacuum chamber will pass down freely through the pipe 9 as the air pipe 10 being open will cause the supply chamber to have a vacuum equal to that of the vacuum chamber proper and the gasoline will descend by gravity. When the gasoline passes down through the pipe 9 it fills the chamber 3 and finally runs over the top of the stand pipe 8 into the chamber 1. After the lower end of the pipe 10 is closed by the gasoline in this manner, the gasoline in the supply chamber will continue to rise being fed through the opening 22 and the continued upward movement of the float 28 will open the valve 30 and cause the normal pumping action of the machine to be resumed. It will be further understood that the float 28 and the valve 30 might very well operate during every operation of the tank under certain condi-

tions, such for instance as climbing a very steep grade when the suction on the tank is at its minimum and the "lift" or elevation from the main rear tank is at its maximum, I therefore do not wish to be limited in my invention to the operation of the valve 30 at any particular time as it is apparent that its operation might take place at any time during the regular operation of the tank 10 when the other devices fail to perform their functions in a manner that will keep the level of the gasoline in the chamber 1 at the proper level. These are all emergency cases however and the ordinary operation of the 15 tank is altogether automatic and needs no attention whatever.

It will of course be understood that either one or the other of the dams may be omitted and the size of the pipe correspondingly reduced, but the presence of the dams allows a large size pipe to be employed and causes a more rapid operation and a much stronger feed of the gasoline from the main tank.

Having thus described my invention what 25 I claim as new and desire to secure by Letters Patent is:

1. In a fuel feeding system the combination with an elevated vacuum tank, of a supply tank, a suction pipe for creating a vacuum in the vacuum tank, a gasoline supply pipe for the vacuum tank, an air vent for the vacuum tank arranged to be covered and uncovered by the fuel in the supply tank, a movable dam in the air vent for obstructing passage in one direction only, and means connecting the vacuum tank and the supply tank.

2. In a fuel feeding system the combination with an elevated vacuum tank, of a supply tank, a suction pipe for creating a vacuum in the vacuum tank, a gasoline supply pipe for the vacuum tank, a vertical air vent pipe for the vacuum tank arranged to be covered and uncovered by the fuel in the supply tank, a dam in the vent pipe comprising a rod with disks on its opposite ends to contact with the ends of the pipe, and means connecting the vacuum tank and supply tank.

3. In a fuel feeding system the combination with an elevated vacuum tank, of a suction pipe for the same, a gasoline supply pipe for said tank, an air vent for the vacuum tank opened and closed by the liquid in the supply tank, an intermediate tank, a pipe connecting the vacuum tank and intermediate tank, a movable dam in said pipe and means connecting the intermediate tank and the supply tank.

4. In a fuel feeding system the combination with an elevated vacuum tank, of a suction pipe for the same, a gasoline supply pipe for said tank, an independent supply tank, an air vent for the vacuum tank

opened and closed by the liquid in the supply tank, and an independent intermediate tank, the vacuum tank resting on the intermediate tank and both of said tanks inclosed in the supply tank.

5. In a fuel feeding system the combination with an elevated vacuum tank, of a suction pipe for the same, a gasoline supply pipe for said tank, a supply tank, an air vent for the vacuum tank opened and closed by the liquid in the supply tank, an intermediate tank, a pipe from the vacuum tank to the intermediate tank, a movable dam in this pipe, means connecting the intermediate tank and the supply tank, and a movable dam in the air vent.

6. In a fuel feeding system the combination with an elevated vacuum tank, of a suction pipe for the same, a gasoline supply pipe for the tank, a supply tank, means connecting the vacuum and supply tanks, an air vent for the vacuum tank opened and closed by the liquid in the supply tank, and means for sealing the supply tank to prevent air reaching the vacuum tank.

7. In a fuel feeding system the combination with an elevated tank having a closed vacuum chamber and a normally open supply chamber, a suction pipe for creating a vacuum in the vacuum chamber, connections allowing air and gasoline to pass between the chambers, a gasoline supply pipe connected to the vacuum chamber, and means for cutting off the air to the supply chamber because of the changing level of the liquid in said chamber.

8. In a fuel feeding system the combination with an elevated tank having a vacuum chamber and a supply chamber, means for creating a vacuum in the vacuum chamber, a gasoline supply pipe connected to the vacuum chamber, and gasoline and air connections between the vacuum and supply chambers including a movable dam or valve for controlling said connections.

9. In a fuel feeding system the combination with an elevated tank having a vacuum chamber and a connected supply chamber, the latter having atmospheric communication, means for admitting air to the vacuum chamber controlled by the level of the liquid in the supply chamber, and a valve or dam controlling communication between the vacuum chamber and the supply chamber.

10. In a fuel feeding system the combination with an elevated tank having a vacuum chamber and a normally open, connected supply chamber, means for causing an intermittent pumping and letting down of gasoline into the supply chamber, and devices for converting the normally open supply chamber into a vacuum chamber when the level of the liquid in said supply chamber falls too low.

11. In a fuel feeding system the combination with an elevated vacuum tank, of a supply tank, a suction pipe for creating a vacuum in the vacuum tank, a gasolene pipe connected to the vacuum tank, an air vent for the vacuum tank arranged to be covered and uncovered by the fuel in the supply tank, and movable mechanical means for controlling the passage of air and gasolene through

the air vent to cause the tank to pump or remain idle.

In testimony whereof I affix my signature in the presence of two witnesses.
